ATTORNEY

UNITED STATES PATENT OFFICE.

LEONARD JAMES FOX, OF CINCINNATI, OHIO.

DESIGN FOR AN EMBLEM.

No. 39,433.

Specification for Design.

Patented July 28, 1908.

Application filed May 22, 1908. Serial No. 434,424. Term of patent 14 years.

To all whom it may concern:

Be it known that I, LEONARD JAMES FOX, a citizen of the United States, and a resident of Cincinnati, in the county of Hamilton and State of Ohio, have invented a certain new, original, and ornamental Design for Emblems, of which the following is a specification.

The accompanying drawing is a view of my newly designed emblem for use as a button, pin, charm, etc.

What I claim is:—

The ornamental design for an emblem, as shown.

LEONARD JAMES FOX.
